(57) **CLAIM**

The ornamental design for a can guard, as shown and described.

DESCRIPTION

The within application is a related patent to Jean Marie Myers and Kermit Lee Myers previously granted U.S. Pat. No. D 487,699.

FIG. 1 is a perspective view of a can guard in accordance with the invention as used on a can;

FIG. 2 is an elevational top view thereof;

FIG. 3 is an elevational side view, all sides being a mirror image, thereof;

FIG. 4 is an elevational top view thereof; and,

FIG. 5 is an elevational bottom view thereof.

The broken lines in the figures are for illustrative purposes only and form no part of the claimed design.
